(57) **CLAIM**

The ornamental design for a laboratory work station, as shown and described.

DESCRIPTION

FIG. 1 is a top perspective view of a laboratory work station embodying my new design;

FIG. 2 is a right side elevational view thereof; the left side being a mirror image thereof;

FIG. 3 is a front elevational view thereof; the back view being a mirror image thereof;

FIG. 4 is a top view elevational view thereof;

FIG. 5 is a bottom elevational view thereof; and,

FIG. 6 is a partial view taken from the circular broken lines shown in FIG. 1.
